UNITED STATES PATENT OFFICE.

OAKLEY SCHUCHERT, OF MINNEAPOLIS, MINNESOTA, ASSIGNOR OF ONE-HALF TO
RALPH SCHUCHERT, OF MINNEAPOLIS, MINNESOTA.

PORTABLE CRANE.

Application filed July 10, 1922. Serial No. 573,904.

To all whom it may concern:

Be it known that I, OAKLEY SCHUCHERT, a citizen of the United States, residing at Minneapolis, in the county of Hennepin and 5 State of Minnesota, have invented certain new and useful Improvements in Portable Cranes; and I do hereby declare the following to be a full, clear, and exact description of the invention, such as will enable others 10 skilled in the art to which it appertains to make and use the same.

My invention provides an extremely simple and highly efficient so-called portable auto crane, which, while capable of more 15 general use, has been particularly designed and is especially serviceable for use in lifting certain parts of an automobile, motor truck, or like vehicle, for the purpose of making repairs.

Generally stated, the invention consists of 20 the novel devices and combinations of devices hereinafter described and defined in the claims.

The improved crane, in its commercial 25 form, comprises a framework mounted on wheels, a pedestal rising therefrom, primary and secondary lifting booms and a windlass connection between the two booms, said parts being combined in a novel manner 30 hereinafter more fully described.

In the accompanying drawings, which illustrate the improved crane, like characters indicate like parts throughout the several views.

Referring to the drawings:

Fig. 1 is a side elevation of the crane, parts of an auto truck or like motor vehicle being indicated by dotted lines;

Fig. 2 is a horizontal section taken on the 40 irregular line 2—2 of Fig. 1, the boom-operating devices being removed; and

Fig. 3 is a transverse section on the line 3—3 of Fig. 2.

The framework 4 of the crane is a 45 rectangular structure, the side beams of which are unconnected at the front ends, so as to form a bifurcated frame adapted to straddle automobile wheels or the like. Rigidly secured to and rising from the frame

50 4 is a trussed mast 5. Said frame 4 is preferably mounted on caster wheels 6. A heavy primary boom 8 is made up of suitably cross-connected bars or members intermediately pivoted to the top of the mast 5, preferably 55 by brackets 9 and 10, respectively, on the

mast and boom, and a pivot shaft 11 passed through said brackets. The long end of the boom 8 projects forwardly and is provided with longitudinally spaced bolt holes 12, through any of which bolts or heavy pins 13 60 and 14 are adapted to be inserted, for an important purpose which will presently appear. By means of a pin 15, a cable-guiding sheave 16 is journaled to the short end of the boom 8. A cable, in the form of a chain 65 17, is anchored at 18 to a brace 5' for the mast 5, is passed over the sheave 16 and thence downward and attached to a windlass drum 19, the shaft 20 of which is journaled in suitable bearings on the brace 5' and is 70 provided with a spur gear 21. The spur gear 21 meshes with a spur pinion 22, the shaft 23 of which is journaled in bearings on the brace 5' and is provided with an operating frame 24. The numeral 25 indicates 75 a retaining dog pivoted to a part of the brace 5' and engageable with the gear 21 to lock the drum 19 in any desired position against unwinding of the chain 17.

A cable-guiding sheave 26 is journaled on 80 the pin 13 and over this sheave is passed a cable in the form of a chain 27, which, at its free end, is provided with a hook 28 detachably engaged with the pin 14. The chain 27 is passed over an intermediate guide sheave 85 29 journaled on the pivot pin 11. The lower end of said chain 27 is attached to a windlass drum 30, the shaft 31 of which is journaled in suitable bearings on the mast 5 and is provided with a spur gear 32. The spur gear 32 90 is in mesh with a spur pinion 33, the shaft 34 of which is journaled on the mast 5 and is provided with an operating crank 35. The numeral 36 indicates a retaining dog pivoted to the mast and engageable with the gear 32 95 to lock the drum 30 in any desired position against the unwinding movements of the cable 27. Suspended on the downwardly looped portion of the chain 27 is a tackle block pulley 37, the shaft of which supports 100 a grapple hook 38.

Pivoted to the lower portion of the mast and located below the main boom 8 is a secondary boom, preferably made up of laterally spaced metal bars 39 and a two-pronged 105 extension, which latter is preferably made of a flat steel bar bent upon itself to form, first, parallel horizontal portions 40, second, parallel vertical portions 40^a and, third, a horizontal looped portion 40^b, which latter, 110

- as shown, supports a cross pin 41, in which may be hung lifting loops 42 or the like. To make this secondary boom extensible, the bars 39 are formed with longitudinal perforations 43 and the bar portions 40 are adjustably pivoted to the said bars 39 by a nut-equipped bolt or rod 44 passed through perforations in the end of said members 40 and through any one of the perforations 43.
- 5 10 Downward movement of the extension member of the secondary boom, in respect to the bars 39, is limited by stop brackets 45 rigidly secured to the ends of the bars 39 and underlying said members 40, leaving 15 the latter free for vertical movements.

A lifting yoke 46 is adjustably connected to the bars 39 of the secondary boom by means of a rod 47 passed through any of the perforations 43 and through perforations in 20 the lower ends of said yoke. When the extension member of the secondary boom is in the position shown in Fig. 1, the bar members 40 will hold the bolt 47 against endwise displacement, but when said bar portions 25 40 are moved upward on the pivot 44, said rod 47 may be moved from one position to another in the perforation 43.

The crane described may be used in a great many different ways in repairing automobiles, trucks and other motor-propelled 30 vehicles and for doing like work. Fig. 1 illustrates the use of the secondary boom to pick up the differential of the truck and to lift the same out of its casing, and here it 35 will be noted that the primary boom projects above the truck body while the secondary boom projects under the truck body and has its end 40^b positioned between the differential and the truck body with the 40 links 42 connected to small lugs or pins, such as customarily found on differentials of the above character. Of course, any other suitable form of grapple may be used to connect the differential to the boom. In the said 45 adjustment shown in Fig. 1, the primary boom 8 becomes a relatively fixed support for the secondary boom 39—40, but the latter may be raised and lowered either by winding up or letting out the chain 27 or by winding up 50 or letting out the chain 17. When the chain 27 alone is manipulated, only the secondary boom will be moved, but when the chain 17 alone is manipulated, both of the booms will be simultaneously moved. Of course, the 55 farther the sheave 37 is adjusted away from the pivots of the primary and secondary booms, the less will be the strain on the chain 27 and on the secondary boom and this is important in lifting very heavy loads.

60 By adjusting the bolts 13 and 14 in the bolt holes 12 of the boom 8 and by adjusting the pin 47 in the holes 43 of the secondary boom, the sheave 37 and grapple hook 38 may be set forwardly or rearwardly to suit the condition of any particular operation.

The main boom 8 may be extended over the top of any ordinary vehicle to lift any part thereof, or it may be extended under certain parts of the vehicle, such as under the body thereof where the latter is to be 70 lifted off from its chassis. In the case of a dumping motor vehicle, when the box is tilted, the main boom may be extended under the tilting box and attached to any of the mechanism below the box. In fact, with the 75 primary and secondary booms connected and operated as described, substantially any part of the motor truck or vehicle may be lifted.

The device is generally efficient as a crane for use in or about automobiles or like places, 80 but is capable of more general use.

What I claim is:

1. A crane of the kind described comprising a base, a mast rising therefrom, a boom pivoted to said mast, cable-anchoring and 85 guiding devices on said boom, a cable attached to said anchor and running over said guide, a windlass for winding up and letting out said cable, a floating sheave mounted on the portion of said cable that is looped 90 between said cable anchor and cable guide, a secondary boom pivoted to said mast, and a grapple supporting the secondary boom from said sheave.

2. A crane of the kind described comprising a base, a mast, horizontally disposed main and secondary booms vertically spaced, the one above the other, and means for independently operating said booms, which supports the secondary boom from the main 100 boom.

3. In a crane of the kind described, the combination with a base and a mast rising therefrom, of a primary boom intermediate pivoted to the upper portion of said mast, a secondary boom pivoted to said mast below said primary boom, a cable and co-operating drum operative to raise and lower said primary boom, and a cable and co-operating drum operative to raise and lower said 105 secondary boom, said latter noted cable being anchored to said primary boom, and the latter having guides over which said latter noted cable passes.

4. In a crane of the kind described, the combination with a base and a mast, of a primary boom applied to and projecting from the upper portion of said mast, a secondary boom located below said primary boom and also pivoted to said mast, a cable anchored to said primary mast, the latter having guide sheaves over which said cable is passed, a windlass for winding up and letting out said cable, a hook-equipped sheave supported on a looped portion of said cable, 120 and a yoke connected to said secondary boom and to said hook.

5. The structure defined in claim 4 in further combination with means for raising and lowering said primary boom.

6. In a crane of the kind described, the combination with a mast and a primary boom projecting from the upper portion thereof, a secondary boom located below said primary boom and pivoted to said mast, means supported from the primary boom and operative to raise and lower said secondary boom.

7. The structure defined in claim 6 in which said secondary boom is provided with a longitudinally adjustable outer end portion that extends first horizontally and then vertically and then terminates in an approximately horizontal portion.

In testimony whereof I affix my signature.
OKEY SCHUCHERT.
